UNITED STATES PATENT OFFICE.

LADIS LEWKOWICZ, OF PARIS, FRANCE.

WINDSHIELD ARTICULATED DEVICE WITH MECHANICAL LOCKING MEANS.

1,413,556.

Specification of Letters Patent. Patented Apr. 18, 1922.

Application filed July 6, 1920. Serial No. 394,360.

To all whom it may concern:

Be it known that LADIS LEWKOWICZ, citizen of the United States, residing at Paris, France, has invented certain new and useful Improvements in Windshield Articulated Devices with Mechanical Locking Means, of which the following is a specification.

The object of this invention is to effect improvement in the construction of the pivotal joints of wind shields to enable the shields to be arranged at will either in vertical or inclined position, and to be secured in either of such positions, a further object 10 being to provide devices of this kind which are simple in construction, which may be readily operated, which are not likely to get out of order, and which can be manufactured at minimum cost.

20 With the above and other objects in view, the invention consists in the construction, combination and arrangement of devices hereinafter described and claimed.

The object of the present invention is 25 therefore to reduce the cost price, and to enable to manufacture in large quantities simple and strong wind-shields.

In the annexed drawing, is shown by way 30 of example—explicative but not limitative—a realization of the invention, in which:

Fig. 1 is a front elevation of a portion a wind shield embodying my improvements.

Fig. 2 is a vertical sectional view of the same.

35 Fig. 3 is a side elevation of the same.

Fig. 4 is a vertical sectional view of the same, on a plane at right angles to that of Fig. 2.

40 My improved wind shield construction includes a member 1 which is affixed to the member 2 which forms the frame of the section 3 of the wind shield. Said member 1 is provided with a recess 4 which has a vertical rear wall 5 and an inclined front wall 6 which converges upwardly toward the rear wall. A recess 4 communicates with a recess 7 in which is located the spring of the locking device. The wind shield 8 is provided at its sides with pivots 10 which are 45 fixed on the members 1. The sides 9 are 50 provided with arms.

The sides 9 are continued in 9^a which operate in the recesses 4. The arm 9^a is held either in the vertical position, or in the inclined position by a locking device, 55 of a special form 11, which can be displaced from the outside by the means of button 12 fixed to shaft 13 counteracting the spring 14 which butts on one side on the locking device and on the other side on the bottom 60 of recess 7. Said spring holds the locking device 11 in position, and is helped by the little spur 15 which locates itself in the little recess 16 provided in part 2 fixed to the section 3.

65 It is easy to understand from the drawings that, whenever it is wished to put the wind-shield in the inclined position when same is in the verticle position, it is sufficient to pull the button 12 so that locking device 70 11 be brought into recess 4, leaving between said recess and the remaining mechanical part enough space to allow arm 9^a to move towards the wind-shield side. When arm 9^a butts against wall 6, it is sufficient in 75 order to hold it in this position to let go of the button 12. The locking device 11 locates itself then against the opposite face 80 of arm 9^a and will hold rigidly said arm against wall 6.

85 It is understood that the present invention is not strictly limited to the example above-shown and represented, but that it can assume various forms, proportions, dimensions and be for or of various materials as need be.

Having now described and ascertained the nature of my invention, what I claim is:

1. In a wind shield, a supporting member having a recess provided with a vertical 90 rear wall and a rearwardly and upwardly inclined front wall, a member pivotally mounted on said supporting member and having an arm extending into said recess between the said walls thereof, and means, arranged in said recess, to bear against said arm and lock the same against either of said walls.

2. In a wind shield, a supporting member having a recess provided with a vertical 100 rear wall and a rearwardly and upwardly inclined front wall, a member pivotally

mounted on said supporting member and having an arm extending into said recess between the said walls thereof, and means, arranged in said recess, to bear against said arm and lock the same against either of said walls, said locking means comprising

extending outwardly from said member and pivotally and axially movable in said supporting member, and a spring active to normally hold the triangular member in engaged position.

In testimony whereof I affix my signature.

LADIS LEWKOWICZ.
